UNITED STATES PATENT OFFICE

EDWIN H. MCLEAN AND JOHN J. UPHUES, OF CHICAGO, ILLINOIS, ASSIGNEES TO
CHICAGO FIRE BRICK COMPANY, OF CHICAGO, ILLINOIS, A CORPORATION OF
ILLINOIS

AIR COOLED WALL CONSTRUCTION

Application filed April 27, 1928. Serial No. 273,274.

Our invention relates to furnace walls, and more particularly to an air-cooled construction for furnace walls in which the refractory elements going to make up the interior portion of the furnace wall are supported in units from an outer wall structure.

It is a purpose of this invention to provide a wall of this character which will relieve the refractory material forming the fire lining of the extreme weight which occurs in furnace constructions where the walls are of considerable height, and to distribute this weight in units upon an outside supporting framework in such manner as to make local repairs of the furnace lining easy to accomplish.

Another object of this invention is to provide, in a structure of this character, means whereby air may be circulated behind the refractory elements with sufficient volume to keep that portion of the wall cool and to cool the supporting steel and cast-iron members so that failure from heat may be avoided.

Another purpose of this invention is to provide, in a furnace wall of this character, novel means to permit expansion between the various units of refractory elements which form the inner lining.

It is also a purpose of this invention to provide means in connection with the supporting elements for the refractory lining for dividing the space between the inner and outer wall structures into a plurality of horizontal zones each of which is maintained separate from the other throughout the circumference of the furnace.

It is also a purpose of this invention to provide, in a furnace wall of this character, wherein the inner refractory lining is supported by an outer framework, novel means for anchoring the refractory lining to the supports and for bracing the supporting elements so as to prevent them from giving independently of each other.

Other objects and advantages of the invention will appear as the description proceeds, in connection with the accompanying drawings. However, it is to be distinctly understood that we do not intend to limit ourselves to the exact details shown and described, but that we intend to avail ourselves

of such modifications as would occur to one skilled in this art and as fall within the scope of the claims.

In the drawings,—

Fig. 1 is a perspective view of a portion of a furnace wall constructed in accordance with our invention;

Fig. 2 is a plan view, partly in section, showing the corner construction between two adjoining walls;

Fig. 3 is a vertical section taken transversely through the furnace wall; and

Fig. 4 is a view similar to Fig. 1 of a modified form.

Referring now in detail to the drawings, the furnace wall is made up of a series of outer uprights indicated by the numeral 5, which in the present instance are in the form of I-beams of sufficient size to carry the structure in its entirety. These I-beams, as indicated in Figs. 1 and 2, are installed vertically at regular intervals around the furnace. A sealing, metallic plate, indicated at 6, is bolted on to these I-beams around the furnace so as to completely surround it, and extends upwardly to such a height as it is desired to extend the wall construction. A series of horizontal beams 7 are bolted to the I-beams through the plate just referred to, and also extend around the circumference of the furnace. These horizontal beams are preferably of substantially H-form and are spaced vertically a distance comparable to the height of the units which are to make up the inner refractory wall. The spaces between the H-beams are then filled with common brick, indicated at 8 in Fig. 1, and between this common brick and the plate 6 a coating of insulating plaster, substantially one-half inch thick, is applied. This coating is indicated in Fig. 1 by the numeral 9. This forms a protection, keeping the heat from attacking the metallic plate and the supporting I-beams 5. In order to support the inner wall, the H-beams have secured thereto horizontally-spaced cast-iron brackets 10, which brackets preferably align vertically in rows and are spaced horizontally along the beams at suitable intervals depending upon the

width of the unit to be supported by the bracket.

The casting 10 has a flat, shelf-like, upper surface, as indicated at 11, and adjacent the free end portion of this shelf there is provided an upstanding flange 13, for a purpose which will presently appear. In applying these brackets and loading them with the refractory tile it is necessary to insure the proper vertical, as well as horizontal, spacing at the free ends, since, if this were not done, one bracket might give sufficiently to communicate its weight to the next unit of refractory material therebelow, and thus subject the tile to a greater pressure than they are capable of withstanding.

It is a well known fact that the refractory tile used for furnace linings cannot stand any great amount of weight. In order to overcome this difficulty, a plurality of small I-beams 14 have their lower ends resting upon the brackets and secured thereto by means of bolts extending through the flanges of the beams and through the flanges 13 on the brackets. The upper ends of the beams are then bolted to flanges 15 on the under surfaces of the brackets, and in this manner the vertical rows of bricks are rigidly connected to each other. Since the beams 14 are spaced inwardly from the free ends 12 of the brackets, these ends may still be used as shelf portions for supporting the refractories thereon.

The refractory units supported on the shelves 12 of the brackets 10 consist of a supporting tile 16 which has a T-slot in one side thereof adapted to fit over the front flange of the I-beam 14. These supporting tile are of a width substantially equal to the distance between centers of the shelf brackets 10, in order that when two of them are placed on horizontally adjacent beams 14, to rest on the corresponding shelves 12, their side faces will be substantially abutting. The upper ends of the beams 14 are spaced a sufficient distance below the shelf 12 to permit the insertion of these supporting tile and the other tile going to make up the unit.

The supporting tile 16 have their front faces curved, as indicated in Fig. 1, so as to divide the tile into the wing portions 17 and 18 and the central, stronger portion 19 directly opposite the T-slot in the tile.

The regular tile 20 which make up the unit are of substantially the same width as the supporting tile and are provided with the same sort of T-slot. The T-slots in these tile are made somewhat larger than the flange of the I-beam in order to make them easy to attach and to permit a certain amount of expansion and contraction while they are on the beam. These tile extend a considerable distance farther from the I-beams than the supporting tile and have their fire-receiving faces substantially in alignment.

Each unit, therefore, is made up of one supporting tile and a number of the regular tile carried thereon, the number of the tile being dependent upon the distance vertically between the brackets 10. In this manner each bracket 10 carries its unit of tile, which is anchored against movement away from the wall by means of the anchor beams 14. The side walls of the units fit snugly against each other so that with the exception of the space between the top regular tile of each unit and the shelf 12 a substantially closed wall structure is provided. There must be a certain amount of space at this point in order to permit for expansion of the tile when the furnace is heated, and in order to protect the shelf 12 means are provided to cut off the direct rays of heat from the furnace and protect the outer steel work. These means consist of expansion joint tile 21, which, as shown in Fig. 1, are of a greater thickness than the regular tile or the supporting tile, and rest upon the top of the upper regular tile of each unit so as to close, in connection with the expansion joint sealing material 22, the joint between vertically adjacent units. The fire-receiving face of this expansion tile aligns vertically with the fire-receiving faces of the regular tile, and the opposite face thereof is formed to co-operate with two horizontally adjacent supporting tile, as shown clearly in Fig. 1.

In this way the tongue portion 23 of the expansion joint tile fits between two adjacent, forwardly extending portions 19 of the supporting tile and forms a very good interlock between horizontally adjacent units.

In order to seal the space between the outer and inner wall structures into a plurality of vertically spaced zones, there are provided partition tile 24 which have their edges resting upon the flat top surfaces 11 of the shelf brackets 10 and extend between these brackets so as to form a substantially-closed, horizontally-extending wall between the inner and outer wall sections. In this way the space is divided into a plurality of zones, and air may be circulated through these zones in large quantities to maintain the structural steel work properly cooled.

At the corners where a side wall and end wall of the furnace come together, as shown in Fig. 2, it is necessary, however, to dispense with the regular shelf brackets because of the overlapping of the adjacent refractories, as indicated at 25 and 26 in Fig. 2. To overcome this, we provide special brackets 27 which hook over the top flange of the H-beams 7 and are slidable therealong so as to be adjustable to fit the partition tile 24 necessary to close the space. It is, of course, necessary to leave a small space, as at 28, between the forward edges of the partition tile and the adjacent refractory tile of the abutting end wall to allow for expansion of the end

wall. This space, however, is quite small, and does not permit any great amount of intermingling of the air between the different zones.

5 This construction may, by the use of special shaped tile, be utilized to introduce air into the combustion chamber from between the inner and outer walls after it is heated by contact with the refractory inner wall.

10 Suitable openings not shown in the outer wall may be provided for introducing air into the several vertically spaced zones and then by utilizing the special tile in the manner illustrated in Fig. 4, ports are provided in the inner wall through which the air enters the combustion chamber.

15 In Fig. 4 the outer wall and the supporting structure are the same as in Figs. 1-3 inclusive. The same supporting tile 16 are employed and the same tile 21 are also used. However, in conjunction with the regular tile 20 the special tile 29, 30, and 31 are used to form tortuous passages through the inner wall in such manner as to prevent direct radiation of heat therethrough to the outer wall. Tile 30 and 31 have the same T-shaped slots as the regular tile 20 for engagement with the beams 14.

20 Tile 30 as shown has one straight side edge 32 which is adapted to abut a vertically extending row of regular tile 20. The opposite side edge of tile 30 is curved as indicated at 33 to cooperate with the adjacent curved side edge 34 of tile 31 and form therebetween a curved passage extending through the inner wall. Side edge 35 of tile 31 is curved in the same manner as side edge 33 of tile 30. Tile 29 has one side edge of the same contour as side edge 34 of tile 31 but has its opposite side edge straight to abut an adjacent row of regular tile 20.

25 The special tile 29, 30, and 31 may be laid in single horizontal rows alternately with regular tile 20 to form small ports or in several adjacent horizontal rows to form larger ports through the inner wall as desired. Also as many of the tile 31 as is desired may be placed between a tile 29 and a tile 30 to determine the distance which the ports will extend along the side or end of a furnace.

30 The outer wall being insulated by the lining 9 and the common brick 8, prevents the escape of heat from the air zones between the walls so that the air passing through these zones and into the combustion chamber through the ports in the inner wall takes up the heat and returns it to the combustion chamber. This serves to cut down the loss of heat as well as to aid combustion materially by having the air heated before it passes into the combustion chamber.

35 It is thought that the above explanation will make the construction and advantages of this invention clear to those skilled in the art, and having thus described our invention

what we claim as new and desire to secure by Letters Patent of the United States is:

1. In a furnace wall, a support, a wall unit consisting of a vertical row of refractory tile carried by said support, a tile supporting shelf spaced above said unit and extending over a portion thereof, a supporting tile resting on said shelf and supporting a second wall unit thereon, said wall units projecting into the furnace beyond the supporting tile, and sealing tile resting on said first named wall unit and extending vertically along the front face of said supporting tile to prevent exposure of said shelf to the heat radiation from the furnace and permit expansion of said units. 70 75

2. A furnace wall structure comprising a plurality of vertically spaced and horizontally abutting wall units each consisting of a plurality of alike refractory tile having their fire receiving faces substantially in alignment, supporting shelves for said units, supporting tile on said shelves upon which said units rest, said supporting tile having their inner faces terminating short of said fire receiving faces, and sealing tile resting on said units and having fire receiving faces aligning with the fire receiving faces of said units and having their opposite faces abutting the inner faces of said supporting tile. 80 85

3. A furnace wall structure comprising a plurality of vertically spaced and horizontally abutting wall units each consisting of a plurality of alike refractory tile having their fire receiving faces substantially in alignment, supporting shelves for said units, supporting tile on said shelves upon which said units rest, said supporting tile having their inner faces terminating short of said fire receiving faces, and sealing tile resting on said units and having fire receiving faces aligning with the fire receiving faces of said units and having their opposite faces abutting the inner faces of said supporting tile, each of said sealing tile resting on a plurality of said units and abutting portions of horizontally adjacent supporting tile. 90 95 100 105 110

4. In a furnace structure consisting of an outer wall and an inner refractory wall made up of units supported by horizontal rows of brackets projecting from said outer wall, flat tile members supported on said brackets to divide the space between said walls into horizontally extending zones, and means at the corners of said furnace for preventing communication between said zones comprising inwardly extending supports carried by said outer wall and slidably horizontally relative thereto, and flat tile members resting on said slidably supports. 115 120 125

5. In a furnace wall, an outer supporting structure having means thereon for supporting an inner wall comprising inwardly extending elements and tile supported by said elements, certain of the horizontally adjacent tile being spaced from each other, and having 130

their opposed spaced faces extending in part horizontally in the same general direction as the fire receiving face of the wall whereby to provide ports through said inner wall which ports are offset intermediate their ends to prevent direct radiation of heat therethrough to the outer structure.

6. In a furnace wall, an outer supporting structure having means thereon for supporting an inner wall comprising inwardly extending elements provided with vertically extending tile engaging members, and tile supported by said elements, certain of the horizontally adjacent tile being spaced from each

10 other whereby to provide ports through said inner wall, said ports having one end offset relative to the other to prevent radiation of heat through said ports direct to the outer structure.

15 7. In a furnace wall, an outer supporting structure having means thereon for supporting an inner wall comprising inwardly extending elements provided with vertically extending tile engaging members and tile sup-

20 ported by said elements, certain of the horizontally adjacent tile being spaced from each other whereby to provide ports through said inner wall, said ports having one end horizontally offset relative to the other to prevent

25 radiation of heat through said ports direct to the outer structure.

8. In a furnace wall, an outer supporting structure having means thereon for supporting an inner wall comprising inwardly ex-

30 tending elements provided with vertically ex- tending tile engaging members and tile sup- ported by said elements, certain of the hori-

35 zontally adjacent tile being spaced from each other and having their opposed spaced faces

40 curved to provide tortuous ports through said inner wall.

9. In a furnace wall, an outer supporting structure having means thereon for sup-

45 porting an inner wall comprising inwardly ex- tending elements provided with vertically ex-

50 tending tile engaging members and tile sup- ported by said elements, certain of the hori-

55 zontally adjacent tile being spaced from each other and having their opposed spaced faces

60 curved to provide tortuous ports through said inner wall, said horizontally adjacent tile being duplicates whereby they

65 are interchangeable one for the other.

10. In a furnace wall, an outer support-

65 ing structure having means thereon for sup-

70 porting an inner wall comprising inwardly ex-

75 tending elements provided with vertically ex-

outer wall and an inner refractory wall made up of units supported by horizontal rows of brackets projecting from said outer wall, flat tile members supported on said brackets to divide the space between said walls into 70 horizontally extending zones, and means at the corners of said furnace for preventing communication between said zones comprising inwardly extending supports carried by said outer wall and horizontally aligning 75 substantially with said brackets, and flat tile members resting on said supports.

In witness whereof, we hereunto subscribe our names this 30th day of March, A. D. 1928.

EDWIN H. MCLEAN.
JOHN J. UPHUES.
